UNITED STATES PATENT OFFICE.

EUGEN HELD, OF STUTTGART, GERMANY.

MAGNETO-GENERATOR.

1,200,939.

Specification of Letters Patent. Patented Oct. 10, 1916.

Application filed June 2, 1914. Serial No. 842,422.

To all whom it may concern:

Be it known that I, EUGEN HELD, a subject of the Emperor of Germany, residing at Stuttgart, Wurttemberg, Germany, have 5 invented a new and useful Magneto-Generator, of which the following is a specification.

The present invention relates to improvements in magneto-generators, and to that 10 type of apparatus, in which generation of potential curves of special form in the induced part of electric machines is accomplished by means of a two-pole field magnet.

15 The main object, that is the generation of potential curves of special form in the induced part of electric machines, is attained by dividing either the pole frame or the armature, or both, longitudinally of the axis 20 of the machine, and displacing the divided parts through a certain angle in the direction of the armature periphery.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed can be made within the scope of what is claimed without departing from the spirit of the invention.

In the drawings—Figure 1 is an end view 35 of a magneto generator machine constructed and arranged so that a special form of potential curve is produced, in the present instance four points of maximum potential per revolution being the result. Fig. 2 is a plan view of the poles. Fig. 3 is a view 40 showing the poles separated. Fig. 4 is a diagrammatic view showing the present invention with the use of a two sectioned armature. Fig. 5 shows a modified arrangement in which the structures shown in Figs. 45 1 and 4 are combined. Fig. 6 is a view of still another modified form in which six points of maximum potential are produced 50 in the winding for each revolution. Fig. 7 shows parts of Fig. 6 in plan. Fig. 8 shows 55 the same parts separated.

Referring to the drawings, and more particularly to Figs. 1, 2 and 3 thereof, the pole shoes of the field magnets 1 and 2 are divided and each pole arm ends in pole 60 shoes 3 and 5, or 4 and 6, the shoes 3 and 4

lying in the front plane and the shoes 5 and 6 lying in the rear plane.

A—A designates the neutral axis for the unlike shoes 3 and 4 lying in the front plane, and B—B is the neutral axis for the pole 65 shoes 5 and 6 lying in the rear plane. The unlike pole shoe pair is displaced, relatively to the pole shoes of the rear plane through the angle X. Between the pole shoes runs a double T-shaped armature 7, the stem 8 65 of which is provided with the inducing winding 9. This arrangement may be modified by dividing the pole shoes longitudinally of the axis not only twice but as many times as may be found desirable, in 70 such a way that the last part is displaced relatively to the same through the angle $\frac{x}{n}$.

Instead of dividing the pole pieces several 75 times in the longitudinal direction and relatively displacing them, the inducing part, the armature, can also be divided along its axis and the sections be relatively displaced.

In the arrangement shown in Fig. 4, between the unlike pole pieces 10 and 11, rotates a wound armature 12, which is divided in two. In the front plane is one part of the armature with the axis D—D and in the rear plane is the other part of the armature 12, with the axis E—E. The axes are relatively displaced through the angle y. The armature spool 13 surrounds the stems of 80 both sections. In this instance also the two parts of the armature may be connected or separated from each other and the armature 85 can also be divided in the same way as to the number of pole shoes.

In the arrangement shown in Fig. 5, the structures as shown in Figs. 1 and 4 are combined. In this case both the pole shoes of the field magnets 14 and the armature 15 are divided longitudinally of the axis and the sections are relatively displaced. The pole shoes are displaced through the angle g and the armature sections through the angle z. When each like pole piece lying in one plane terminates in several pole shoes, it is possible to produce in a simple way a larger number of points of maximum potential per revolution, as is 90 clearly evident from the foregoing description and diagram.

In the form shown in Figs. 6, 7 and 8, the unlike pole pieces lying in the front plane, terminate in the pole shoes 16 and 17, and 110

the pole pieces lying in the rear plane terminate in the pole pieces 18 and 19. The neutral axes E—E and G—G are relatively displaced through 90 degrees. When a 5 wound armature 21 is rotated between the pole shoes, six points of maximum potential are produced in the winding per revolution.

In view of the foregoing, it is evident that 10 the generator can be constructed with the pole pieces having like coaxial portions at opposite sides of a plane at right angles with the axis of the armature shifted bodily at an angle relative to one another, or the armature may be provided with like coaxial 15 portions at opposite sides of the plane at right angles with the axis of the armature shifted bodily at an angle relative to one another, or the pole pieces and armature can each be provided with portions as above indicated. 20 What is claimed is:

1. In a generator, two opposite similarly-shaped pole pieces, and an armature rotatable between them, the pole pieces having like coaxial portions at opposite sides of a plane at right angles with the axis of the armature shifted bodily at an acute angle relative to one another, the portions at one 25 side of said plane being shaped similar to and spaced the same distance apart as the

portions at the opposite side of said plane, so said portions having curved faces extending through relatively large equal arcs.

2. In a generator, two opposite similarly-shaped pole pieces, and an armature rotatable between them, the pole pieces having like coaxial portions at opposite sides of a plane at right angles with the axis of the armature shifted bodily at an acute angle relative to one another, the portions at one side of said plane being shaped similar to and spaced the same distance apart as the 35 portions at the opposite sides of said plane, said portions having curved faces extending through relatively large equal arcs, the armature having portions at opposite sides 40 of said plane shifted bodily at an acute angle relative to one another and of the same shape, said portions of the armature having curved faces extending through relatively 45 large equal arcs. 50

In testimony that I claim the foregoing as my own, I have hereto affixed my signature in the presence of two witnesses.

EUGEN HELD.
